UNITED STATES PATENT OFFICE.

JOHN WILSON BROWN, JR., OF PHILADELPHIA, PENNSYLVANIA, ASSIGNOR
TO THE ENTERPRISE MANUFACTURING COMPANY OF PENNSYLVANIA,
OF SAME PLACE.

DESIGN FOR A CASING FOR PUMPS.

SPECIFICATION forming part of Design No. 27,698, dated September 28, 1897.

Application filed March 15, 1897. Serial No. 627,696. Term of patent 14 years.

To all whom it may concern:

Be it known that I, JOHN WILSON BROWN, Jr., a citizen of the United States, residing in Philadelphia, Pennsylvania, have invented a certain new and useful Design for Molasses-Pump Casings, of which the following is a specification.

My design for the casing of a molasses-pump is clearly illustrated in the accompanying drawing, in which the figure is a side view of the pump.

The essential feature of the design is the long barrel, having at the top an overhanging head and at the base an ornamental foot. A is the barrel, circular in cross-section and having at the top a curved neck C and ornamented at each end by rounded ribs c c'.

The head B is of the peculiar ornamentation shown.

The foot a is circular in cross-section and is larger than the barrel and has a series of slots a', rounded at the upper end, giving it the design as shown. A circular sleeve D is arranged on the barrel and has two flat wings d at its lower end, as shown.

I claim—

The design for the casing of a pump, as described and shown in the accompanying drawing.

In testimony whereof I have signed my name to this specification in the presence of two subscribing witnesses.

JOHN WILSON BROWN, JR.
